(57) **CLAIM**

The ornamental design for a device for storing papers or the like, as shown and described.

DESCRIPTION

FIG. 1 is a perspective view of a device for storing papers or the like.

FIG. 2 is a front view of the device of FIG. 1.

FIG. 3 is a left side view of the device of FIG. 1.

FIG. 4 is a right side view of the device of FIG. 1; and, FIG. 5 is a top view of the device of FIG. 1.

The broken lines in FIGS. 1-5 are for environmental purposes only and form no part of the claimed design.

The “stipple” shading that can be seen in FIGS. 1, 2, and 5 is used to represent a type of surface material.

1 Claim, 3 Drawing Sheets

FIG. 1

FIG. 2

FIG. 3

FIG. 4
